UNITED STATES PATENT OFFICE

2,095,197

TYPOGRAPHICAL MACHINE

William M. Rapp, deceased, late of the county of Gloucester, and State of New Jersey; by Edward Rapp, administrator, Westmont, N. J., assignor to Edward Rapp, Westmont, N. J.

Application August 27, 1936, Serial No. 98,164

5 Claims. (Cl. 199—30)

This invention has to do with typographical machines, and is particularly concerned with that type of machine illustrated and described in the patent to Rapp, Number 1,178,178, dated April 4, 1916.

At the present time there is available to the public a machine which is designed and manufactured substantially in accordance with the disclosure of the Rapp patent above referred to.

10 Such a machine ordinarily includes a triangular framework on which is slidably mounted an assembler slide. Associated with this assembler slide is the usual braking device, and in the now known types of machine the framework carries a line stop which controls the length of a line, together with an attachment for holding the slug. Associated with the latter is a suitably graduated scale which cooperates with a scale on the assembler slide to provide vernier readings.

20 At the present time some little difficulty is being experienced due to the tie-up of the line stop with the device for holding the slug, inasmuch as no suitable provision is made for accommodating wear in the star wheel, which is included in a typographical machine of this type.

25 Accordingly, this invention has in view as an important objective the provision of a typographical machine of this type, in which the line stop for controlling the length of a line is mounted on the framework entirely independently of the attachment of the slug holding device thereto.

30 More particularly this invention has in view as a further object the provision of a typographical machine of this type, in which the slug holding device and associated graduated scale is adjustably mounted on the framework, in order to provide for adjusting the said device to allow for wear which may take place on the star wheel.

35 40 Yet another object of the present invention is to provide a space band buffer which is carried by the framework, and which is adjustable thereon.

45 Various other more detailed objects and advantages of the invention will in part become apparent, and in part be hereinafter stated, as the description of the invention proceeds.

The invention, therefore, comprises a typographical machine of the type shown in the said 50 Rapp patent, and which comprises a framework on which is mounted an assembler slide and associated mechanism. A line stop is carried by the framework, and a slug holding device having a scale for vernier readings is adjustably mounted 55 on the framework in proper position with respect

to the slide. An adjustable space band buffer is also mounted on the framework.

For a full and more complete understanding of the invention, reference may be had to the following description and accompanying drawing 5 wherein—

Figure 1 is a side view of a typographical machine made in accordance with the precepts of this invention.

Figure 2 is a detailed rear view of the framework of the machine,

Figure 3 is a detailed view in perspective of a lip extension for adapting the machine to inter-type work, and

Figure 4 is a bottom plan view of the slug holding device.

Referring now to the drawing, wherein like reference characters denote corresponding parts, the framework of the typographical machine is referred to generally by the reference character 20 F. The framework F carries a space band buffer in the form of a lever arm 10 which is pivotally mounted at 11 on a plate 12 that is also formed with a stop 13 for limiting pivotal movement of the arm 10. The plate 12 is provided with a slot, 25 shown at 14, and a headed screw indicated at 15 extends through the slot 14 of the plate 12 and is anchored to the framework F in a well-known manner. It is evident that the slot 14 will permit of adjustment with the plate 12 with respect 30 to the framework F.

Slidably mounted in the framework F is an assembler slide, designated 16, which carries at one end an upright projection 17 which normally cooperates with the star wheel of a machine of 35 this type in a manner clearly illustrated and described in the said Rapp patent. The assembler slide 16 is provided with the usual graduated scale indicated at 18.

The framework F carries, in a position above 40 the slide 16, a line stop referred to generally by the reference character L. This line stop comprises a screw member 19 having a nut at 20, and which is carried by an ear 21. It is this line stop 45 L which controls the length of the line which is set up by the machine.

Disposed substantially beneath the line stop L is a slug holding device which is referred to in its entirety by the reference character S. This slug holding device comprises a main body member 22 having a slot 23 through which extends said screw 24 that is anchored to the framework F. It is evident that the connection comprising the slot 23 and screw 24 permits of adjustment of the 50 55

device S with respect to the framework of the machine.

5. The main body portion 22 comprises a graduated scale 25 which cooperates with the scale 18 on the assembler slide to provide vernier readings. A spring clip member, indicated at 26, functions to maintain a slug (not shown) assembled on the device S.

The typographical machine illustrated in the 10 drawing and described in the specification is primarily intended for "linotype" work, but also may be adapted to "intertype" work by incorporating as a part of the structure the lip extension shown in Figure 3, and indicated at 27.

15. As shown in Figure 2, the rear side of the framework F is provided with a channel construction, designated 28, and the lip extension 27 has an offset portion 29 that fits in the channel 28. Openings 30 and 31 provide for the passage of a 20 fastening element such as a screw (not shown) therethrough to maintain the parts assembled.

25. When wear has occurred on the star wheel the same may be accommodated by adjustment of the slug holding device S with respect to the framework F, due to the slot 23. At the same time this adjustment is entirely dependent of the condition of the line stop L.

30. While a preferred specific embodiment of the invention is hereinbefore set forth, it is to be clearly understood that the invention is not to be limited to the exact construction illustrated and described, because various modifications of these details may be provided in putting the invention into practice within the purview of the appended 35 claims.

What is claimed is:

1. A typographical machine of the character described comprising a framework, an assembler slide slidably mounted in the framework, a line 40 stop carried by the framework adjacent to said assembler slide, and a slug holding device independent of the line stop and adjustably mounted on the framework.

2. A typographical machine of the character

described comprising a framework, an assembler slide slidably mounted in the framework, a line stop carried by the framework adjacent to said assembler slide, and a slug holding device independent of the line stop and adjustably mounted 5 on the framework, said assembler slide being provided with a graduated scale, and said slug holding device being provided with a scale for cooperating with the scale on the assembler slide to provide for vernier readings.

3. A typographical machine of the character described comprising a triangular framework, an assembler slide slidably mounted in the framework, said assembler slide being provided with a graduated scale, a line stop for the assembler slide 10 carried by the framework, a slug holding device independent of the line stop and formed with a slot, and a retaining screw passing through said slot and being anchored in the framework, said slot and screw providing for adjustment of the 15 slug holding device with respect to the framework, said slug holding device being provided with a graduated scale which cooperates with the scale in the assembler slide to provide vernier readings.

4. In a typographical machine of the character described, a framework, a plate member adjustably carried by said framework, and a space band buffer pivotally mounted on said plate member, said plate member being formed with a stop for limiting pivotal movement of the space band 20 buffer.

5. In a typographical machine of the character described, a triangular framework, a plate formed with a slot, a retaining screw extending through said slot and being anchored to the framework, 25 said plate being formed with a projection constituting a stop, and a lever arm constituting a space band buffer pivotally carried by said plate, the pivotal movement of said arm being limited by said stop.

40 EDWARD RAPP,

Administrator for the Estate of William M. Rapp,
Deceased.
